UNITED STATES PATENT OFFICE.

EMERSON CURRIE, OF VANCOUVER HEIGHTS, BRITISH COLUMBIA, CANADA.

HAMMER.

1,110,186.

Specification of Letters Patent. Patented Sept. 8, 1914.

Application filed November 26, 1913. Serial No. 303,254.

To all whom it may concern:

Be it known that I, EMERSON CURRIE, a citizen of Canada, residing at Vancouver Heights, in the Province of British Columbia and Dominion of Canada, have invented new and useful improvements in Hammers, of which the following is a specification.

This invention is directed to improvements in hammers, and has particular reference to that class of devices known as claw hammers.

The primary object of the invention is the provision of a hammer of the above mentioned character wherein the slot is so arranged as to provide relatively long and short claw members respectively, the former being constructed to provide a broad cutting edge for the tool.

A further object of the invention is the provision of a device of this character wherein the slot defining the claw extends diagonally of the head opening at one side thereof to provide relatively long and short claw members respectively, the former having a broad end portion to provide a cutting edge for the tool of relative maximum width, while the latter terminates rearwardly of the plane of the cutting edge so as not to contact with the material being cut.

With these and other objects in view which will appear as the nature of the invention is better understood, the same consists in the specific construction and arrangement hereinafter more fully described, and particularly pointed out in the appended claim.

In the drawing forming a part of this application and in which like numerals indicate similar parts in the several views; Figure 1 is a perspective view of my improved hammer with the handle partly broken.

Fig. 2 is a top plan view. Fig. 3 is a side elevation.

Referring more particularly to the drawing, 5 indicates the head of the hammer provided with the usual opening 6 into which is secured the handle 7 in ordinary and well known manner. The claw 8 is defined by the provision of a slot 9 which as shown 45 extends diagonally from a point of approxi-

mately central of the head 5, and opens at one side thereof. Owing to the particular disposition of the slot 9 the claw 8 consists of relatively long and short claw members 10 and 11 respectively for the purpose which 55 will hereinafter be described. The outer wall of the member 10 and the inner wall 12 of the slot 9 are curved outwardly in opposite directions from a point in line with the inner end of the slot throughout the remaining portion of the length of the member to provide an end portion of relative maximum width which is sharpened to provide a cutting edge 13 for the tool. The inner wall 14 of the member 11 is curved 65 in the same direction as the wall 12 and terminates at the point of juncture with the outer wall 15 of said member rearwardly of the plane of the cutting edge 13 so as not to come in contact with the material being 70 cut, and to further provide for this end it will be noted that the width of the cutting edge 13 exceeds that of any other portion of the head 5 and terminates at one end approximately in line with the outer wall 75 15 of the member 11. Of course as will be readily understood the claw is adapted for extracting nails and the like, but it will be manifest that by the specific disposition of the slot 9 provision is made for the member 80 10 whose construction is such as to permit of its use in the capacity of an ax, hatchet or the like. It will be further obvious that owing to the relative dimension of the members 10 and 11 and the arrangement of the 85 slot 9, the said member 11 terminates considerably rearwardly of the cutting edge 13 so as to be protected from injuring and interfering with the work by coming in contact with the same when the device is used 90 as an ax or the like.

It is believed that from the foregoing description, when considered in connection with the drawing, the nature of my invention will be understood by those skilled in the art without further explanation, and therefore the same has been omitted.

What I claim is:

A tool of the class described, comprising a head having a diagonally arranged slot 100

defining a claw consisting of relatively long and short members respectively, and said long member having a broad end portion of relative maximum width to provide a cutting edge for the tool and terminating in a line with the outer edge of said short member.

In testimony whereof I affix my signature in presence of two witnesses.

EMERSON CURRIE.

Witnesses:

J. HUMSTRUGH,
C. W. HENDERSON.
